EDWARD P. SHELDON, OF BROOKLYN, NEW YORK, ASSIGNOR, BY MESNE ASSIGNMENTS,
TO R. HOE AND CO., INC., OF NEW YORK, N. Y., A CORPORATION OF NEW YORK.

ADHESIVE APPLYING AND DRYING MECHANISM FOR SHEETS.

Application filed August 25, 1923. Serial No. 659,287.

This invention relates to certain improvements in machines for applying adhesive to sheets and for thereafter drying the gummed sheets.

5 These machines are used for applying adhesive to printed sheets, such for instance, as sheets of stamps, these gummed sheets being dried after the adhesive has been applied thereto.

10 In machines heretofore used for this purpose the drying of the gummed sheets has been effected by passing them through a drying chamber to which steam or hot air was admitted for effecting the drying action.

15 The drying action effected through these agencies was slow and required a drying chamber of such length that it was difficult to install a chamber in many plants and even where space could be provided the drying took up much space needed for other mechanisms.

20 It is the especial object of the present invention to provide a machine for gumming and drying sheets in which the drying chamber is so arranged and heated that a drying action is very quickly effected so that a drying chamber of small dimensions will adequately dry the sheets thus saving valuable space which is of great importance in printing plants.

25 It is a further object of the invention to provide a gumming and drying machine having improved structural features.

30 With these and other objects not specifically referred to in view, the invention consists in certain novel parts, arrangements and combinations, which will be fully described in connection with the accompanying drawings, and the novel features thereof pointed out in the claims hereunto appended.

35 In these drawings—

Figure 1 is a side elevation with the front frame removed and partly in section of the feed and gumming end of a gum applying machine the drier being shown in section and partly broken away.

40 Figure 2 is a similar view of the delivery end of the machine.

45 Figure 3 is a plan view partly in section of one end of the drier.

50 Figure 4 is a sectional view taken on line 4—4 of Fig. 3.

55 Figure 5 is a detail sectional view of certain supports employed in the drier.

Referring now to these drawings, the parts

of the mechanism will be supported in side frames both of which marked 1 are shown in the drawings.

The machine illustrated includes the usual sloping feedboard 2 down which the sheets are fed against a front stop 3. The sheets to be gummed are carried through the gumming and drying mechanism by means of a travelling carrier shown as a pair of chains 4, 5 which pass over a driving sprocket 6 mounted 60 on a shaft 7 suitably journaled in the frame of the machine at one end and over a sprocket 8 on a shaft 9 suitably journaled in the machine frame at the delivery end.

These carrier chains are provided with 70 sheet taking devices which take the sheet and carry it in a flat position through the gumming and drying mechanism to the delivery end of the machine these sheet taking devices being arranged so as to take the sheet on each 75 side at its head and tail. While these sheet taking devices may be of various characters, in the particular construction illustrated they are in the form of grippers which are mounted on gripper frames 10 carried by the chains. 80 These grippers comprise a fixed jaw 11 and a movable jaw 12, the movable jaw being operated from a cam roll 13 which co-operates with a suitable cam to open and close the grippers to take and release the sheets. 85

These grippers take the sheets from the feedboard and carry the sheets beneath the gumming mechanism which includes a gumming roll 14 to which gum is supplied from a fountain 15, the gum applying roll 14 working against an abutment in the form of a cylinder 16 suitably mounted on a shaft 17 supported in the side frames of the machine.

After the adhesive is applied to the sheet the sheet is carried by the grippers through 90 the drying mechanism which is located closely adjacent the gumming devices. In accordance with the invention this drier is constructed so as to effect a quick drying of the gummed sheet so that the space required by the drier may be minimized as far as possible, and to effect this the drier is provided with electrical heating units over which the sheet is passed flatwise under the control of the grippers. While the specific construction of the drier and the type of electrical heating units employed may be somewhat varied, the construction shown in the drawings has been found effective in practice. In the construction illus- 100 110

trated, the drier is in the form of a rectangular chamber 18 of metal, the walls of which are or may be covered with heat insulating material as asbestos, indicated by 5 the numeral 19. The ends 20, 21 of this chamber are open, as indicated at 22 to permit the passage therethrough of the chains and the gripper blocks carried thereby. This drier may be supported in any suitable 10 manner in the side frames 1 before referred to, as by means of flanges 23 through which pass bolts 24 in the frames.

Extending through the drier are supporting beams 25 and extending beneath the 15 drier are small supporting beams 26, three of these latter being shown. These supporting beams are or may be mounted in any suitable manner. In the particular construction illustrated they are supported 20 from hanger plates 27 carried on rods 28 and 29 suitably supported adjacent the front and rear ends of the drier in the side frames, before referred to. In the best constructions the upper pair of beams 25 extend beyond 25 the drier at each side, as indicated at 30, 31 in Figs. 1 and 2, and these upper beams are T-shaped in cross-section forming in effect a track. These beams thus provide a surface on which may ride rounded portions 30 32 on the chains and prevent the chains from sagging as they pass under the gumming mechanism through the drier and to the delivery end of the machine.

In accordance with the invention electrical 35 heating elements are provided for heating the drier so as to effect a rapid drying of the gummed sheet. While these means may be varied somewhat, in their best arrangement these means will be located inside 40 the drier and in the preferred embodiment of the invention comprise preferably a series of plates 33, two of these plates being shown, these plates being connected to a suitable source of electricity by a line circuit indicated by the wires 34, 35. These plates 45 extend across the drying chamber preferably substantially the length of the drying chamber, and there is thus arranged a wide heating surface by which a very rapid drying 50 of the gummed sheet takes place and consequently the space required by the drying chamber is greatly reduced. The plates may be supported in the chamber in any suitable manner. In the particular construction 55 illustrated, these plates are supported on brackets 36 secured to the supporting beams 25, before referred to, the feet 37 of the brackets passing inwardly toward each other, as shown in Fig. 4. The plates 60 are provided with projections 38 which rest on the feet of the brackets, being suitably insulated therefrom.

After the sheets leave the drier they are delivered from the machine in any suitable 65 manner. In the best constructions there is

provided a bending device over which the sheet is bent or turned so as to smooth out the sheet and prevent the gummed sheet from rolling. While the particular construction for effecting this may be varied, 70 as illustrated the head of the sheets on being released by the front grippers passes into the control of a pair of forwarding rolls 39, 40 suitably mounted on shafts 41, 42 in the side frames of the machine. 75

These forwarding rolls take the head of the sheet before it is released by the grippers so that the sheet is positively controlled. From the forwarding rolls the sheet passes between the sheet guides 43 and a bending 80 plate 44, this bending plate having a downwardly extending lip 45. The sheet is forwarded over this bending plate until the front edge of the sheet projects a short distance beyond the lip 45. At this time a tucking blade 46 is caused to tuck the projecting end of the sheet into the bite of a pair of drawing off rolls 47, 48 suitably mounted on shafts 49, 50, the shaft 49 being mounted in the side frame of the machine. 85

These drawing off rolls 47, 48 act to pull the sheet around the edge of the lip 45 and thus act to straighten the sheet so that it will not roll up when it is finally delivered.

The tucking blade may be operated in various ways. In the particular construction illustrated, the tucking blade is operated by an arm 51 mounted on an arm 52 pivoted at 53 in the frame of the machine. The lower end of this arm is provided with a cam roll 100 54 which is actuated by a cam 55 (see Fig. 2) on a shaft 56. To rock the arm and cause the tucking blade to force the end of the sheet into the bite of the rolls 47, 48, the roll 48 is or may be as shown carried on the arm 105 52 so that when the arm is in its out position a clear space is left for directing the end of the sheet between the rolls.

The dried and straightened sheet passes the rolls 47, 48 to a final delivery, which 110 may be the ordinary fly delivery indicated at 57, the sticks of this delivery delivering the sheets into the usual box 58.

The various parts of the mechanism may be driven in any usual or suitable manner. Referring to Figs. 1 and 2 there is shown a main power shaft 60 driven from any suitable source of power, not shown, the shaft of which is provided with a gear 61. This gear meshes with a gear 62 which, in turn 115 meshes with a gear 63 on the sprocket wheel 6, thereby driving this sprocket. The gear 62 also meshes with a gear 64 on the shaft 17 of the abutment roll 16, before referred to, driving this roll and this gear 64 also 120 drives through a gear 65 the gumming applying roll 14, before referred to. The shaft 9 of the sprocket wheel 8 is provided with a gear 66 which meshes with an intermediate 125 gear 67. This intermediate is in mesh with a 130

5 gear 68 on the roll shaft 41 and with a gear 69 on the roll shaft 49 whereby these two rolls are driven. The shaft 9 also is provided with a gear 70 which meshes with an intermediate 71 which in turn meshes with a gear 72 on the cam shaft 56.

10 With the construction shown and described a very compact and efficient gumming and drying mechanism for sheets has been provided, and one which effects a very rapid and effective drying of the sheet.

15 While the invention has been shown and described in its preferred form, it will be understood that various changes may be made in the arrangement and construction of the different parts and that various types of electrical elements may be employed in the drier without departing from the invention set forth in the claims hereunto annexed.

20 What I claim is:

1. The combination of a travelling sheet carrier having means for holding a sheet to which an adhesive has been applied, forward- 25 holding means entirely release it, a bending plate over which the sheet is drawn, and a delivery.

2. The combination of a travelling sheet carrier having means for holding a sheet to which an adhesive has been applied, a bending plate over which the sheet is drawn, and a pair of drawing rolls below and closely adjacent the plate for drawing the sheet, one of 35 these rolls being mounted to swing toward and away from the other.

3. The combination of a travelling sheet carrier having means for holding a sheet to which an adhesive has been applied, a plate having a bending lip, and a pair of drawing off rolls below the plate acting to draw the sheet over the bending lip. 40

4. The combination of a travelling sheet carrier having means for holding a sheet to which an adhesive has been applied, a bending plate, a pair of drawing off rolls acting 45 to draw the sheet over the bending plate, and a tucking blade for tucking the end of the sheet into the bite of the rolls.

5. The combination of a travelling sheet carrier having means for holding a sheet to which an adhesive has been applied, a pair 50 of rolls to which the sheet is delivered from the holding means, a bending plate, a pair of drawing off rolls acting to draw the sheet over the plate, and means for directing the 55 end of the sheet into the bite of the drawing off rolls.

6. The combination of a travelling sheet carrier having means for holding a sheet to which an adhesive has been applied, a bending plate, a pair of drawing off rolls below and adjacent the plate and acting to draw the sheet over the plate, a tucking blade for tucking the end of the sheet into the bite of the rolls, and means for effecting a separation 60 of one of the rolls from the other. 65

In testimony whereof, I have hereunto set my hand.

EDWARD P. SHELDON.
